UNITED STATES PATENT OFFICE

120,771

DESIGN FOR A BEATER FOR EGGS, CREAM, OR THE LIKE

Myron J. Zimmer, Chicago, Ill., assignor to The Edward Katzinger Company, Chicago, Ill., a corporation of Illinois

Application September 25, 1939, Serial No. 87,381

Term of patent 14 years

To all whom it may concern:

Be it known that I, Myron J. Zimmer, a citizen of the United States, residing at Chicago, in the county of Cook and State of Illinois, have invented a new, original, and ornamental Design for a Beater for Eggs, Cream, or the like, of which the following is a specification, reference being had to the accompanying drawing, forming a part thereof.

In the drawing:

Fig. 1 is a side elevational view of a beater for eggs, cream or the like, showing my design.

Fig. 2 is a top plan view, on an enlarged scale,
of the beater head element shown in full lines
in Fig. 1; and

Fig. 3 is a cross-sectional view thereof, taken along line 3—3 of Fig. 2.

The dominant feature of the design resides in the portion shown in full lines.

I claim:

The ornamental design for a beater for eggs,
cream, or the like, as shown and described.

MYRON J. ZIMMER.
